Inventor
W. White,

By *Clarence A. O'Brien*

Attorney

UNITED STATES PATENT OFFICE.

WILLIAM WHITE, OF NEWARK, NEW JERSEY.

ADJUSTABLE PIPE CLEANER.

Application filed April 23, 1926. Serial No. 104,066.

The present invention relates to a cleaner for the bowls of smoking pipes and has for its principal object to provide an adjustable structure that may be used in different size bowls and is capable of easy and quick adjustment in an accurate manner.

Another very important object of the invention is to provide a cleaner of this nature which overcomes the disadvantages and objections common to many contrivances heretofore devised for a similar purpose and to provide a cleaner which is simple in construction, reliable in operation, possessing the capacity for long and continued service, not likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

25 In the drawing:—

Figure 1 is an elevation of the cleaner embodying the features of my invention.

Fig. 2 is a longitudinal section therethrough, and

30 Fig. 3 is a transverse section therethrough. Referring to the drawings in detail, it will be seen that 1 designates the body of the cleaner which is provided with a longitudinally extending bore 2 having an enlarged portion 3 at its bottom end and terminating in an enlarged recess 4 at its upper end. A plurality of slots 5 are provided in the lower end of the body and radiate from the larger portion 3 of the bore 2. A handle bar 6 pierces a transversely disposed opening provided in the upper portion of the body 1 and is provided with a transversely extending bore 7 in registry with the bore 2. A shaft 8 pierces the bores 2 and 7 and extends through the recess 4 and through the enlarged portion 3.

45 An enlarged threaded portion 9 is provided on the shaft 8 within the enlarged portion 3 of the bore 2 and is threadedly engaged therewith. At the lower end of the shaft 8, there is provided a head 10 having an enlargement 11 at the lower end thereof. A knob 12 is fixed on the upper end of the shaft by means of a pin 13. This knob moves in the recess 4. A plurality of scraper blades 14 are pivoted on a ring 15 disposed

in a groove 16 provided exteriorly of the body 1 intermediate the ends of the slots 5. There is one blade movable in each slot 5. The interior edge of each blade is provided adjacent its lower end with an inclined surface 16' and adjacent its upper end with a notch or overhanging portion 17. The enlargement 11 is adapted to engage the inclined surfaces 16' while the upper end of the head 10 is adapted to engage the overhanging portions 17.

From the above detailed description, it will be seen that by turning the knob 12 in one direction, the shaft 8 will move 70 downwardly, causing the enlargement 11 to engage the inclined surfaces 16' thereby spreading the scraper blades, outwardly. By rotating the knob 12 in the opposite direction, the shaft 8 will be moved upwardly, 75 causing the upper end of the head 10 to engage the overhanging portion 17, thereby swinging the scraper blades 14 inwardly.

The bottom of the recess 4 limits the movement of the shaft 8 in one direction, 80 since it forms an abutment for the bottom end of the knob 12. The shoulder formed by the upper end of the enlarged bore 3 with the bore proper 2 forms an abutment for the upper end of the enlarged threaded portion 9 of the shaft 8, thereby limiting the upward movement of this shaft.

85 It is thought that the construction, operation, and advantages of this invention will now be clearly understood without a more detailed description thereof. It will be apparent that by placing the bladed end of the contrivance in the pipe bowl and then spreading the blades, said blades will engage the cups of crust formed in the bowl 90 so that by rotating the whole contrivance, the bowl will be cleaned. This process may be continued until all of the crust is removed, or as much of it is removed as may 95 be desired.

100 The present embodiment of the invention has been disclosed in detail, since in actual practice it attains the features of advantage enumerated as desirable in the statement of the invention and the above description.

105 It will be apparent that numerous changes in the details of construction, and in the combination and arrangement of parts may be resorted to without departing from the spirit or scope of the invention as herein-after claimed, or sacrificing any of its 110 advantages.

Having thus described my invention, what I claim as new is:—

1. A pipe cleaner of the class described including an elongated body having a longitudinally extending bore and slots radiating from the bore at the lower end of the body, blades pivoted in the slots and provided with slanting inner edges, a spreader bar slideable through the bore so that it may be moved for engaging the slanting edges of the blades to spread them.
2. A pipe cleaner of the class described including an elongated body having a longitudinally extending bore and slots radiating from the bore at the lower end of the body, blades pivoted in the slots and provided with slanting inner edges, and a shaft threaded thru the bore and having an enlargement for engaging the slanting edges of the blades to spread them apart and also provided with a shoulder for engaging notches provided in the blades for contracting them.
3. A pipe cleaner of the class described including an elongated body provided with a bore and slots, a shaft threaded through the bore and provided with a head, a plurality of blades pivotally mounted in the slots and engageable by the head to spread the blades apart upon the movement of the shaft in one direction, the end of the body being provided with a recess, a knob fixed to the shaft and movable in the recess, the bottom of said recess limiting the movement of said knob in one direction.
4. A pipe cleaner of the class described including an elongated body having a longitudinally extending bore, the lower portion of which is enlarged and provided with slots in extension of the bore and
- radiating therefrom, a shaft rotatable in the bore and having an enlargement threadedly engaged with the enlarged portion of the bore, a knob on the shaft, a head on the shaft adjacent the slots, an enlargement on the head, a plurality of jaws pivoted in the slots and provided with inclined surfaces for engagement by the enlargement of the head, and notches for engagement by one end of the head so that by screwing the shaft, the blades may be either contracted or expanded.
5. A pipe cleaner of the class described including an elongated body having a longitudinally extending bore, the lower portion of which is enlarged and provided with slots in extension of the bore and radiating therefrom, a shaft rotatable in the bore and having an enlargement threadedly engaged with the enlarged portion of the bore, a knob on the shaft, a head on the shaft adjacent the slots, an enlargement on the head, a plurality of jaws pivoted in the slots and provided with inclined surfaces for engagement by the enlargement of the head and notches for engagement by one end of the head so that by screwing the shaft the blades may be either contracted or expanded, said body being provided with a recess for receiving said knob.
6. A pipe cleaner of the class described including an elongated body having a plurality of slots in one end thereof, an annular groove about the exterior surface thereof, a plurality of blades having openings, a ring extending through the openings and seated in said groove.

In testimony whereof I affix my signature,

WILLIAM WHITE.
